(57) **CLAIM**

The ornamental design for a handle for a pitcher, as shown and described.

DESCRIPTION

FIG. 1 is a top, front, left side perspective of a handle for a pitcher showing our new design in the environment of a pitcher drawn in broken lines which forms not part of the claimed design.

FIG. 2 is a top, front, left side perspective view of the handle for a pitcher shown above;

FIG. 3 is a bottom, front, right side perspective view thereof;

FIG. 4 is a top plan view thereof;

FIG. 5 is a bottom plan view thereof;

FIG. 6 is a rear elevational view thereof;

FIG. 7 is a left side elevational view thereof, the right side

elevational view being a mirror image of FIG. 7; and,

FIG. 8 is a front elevational view thereof.
